LEWIS COLWELL, OF NEW YORK, N. Y.

Letters Patent No. 77,359, dated April 28, 1868.

IMPROVED VALVE FOR SUGAR-PANS.

The Schedule referred to in these Letters Patent and making part of the same.

TO ALL WHOM IT MAY CONCERN:

Be it known that I, LEWIS COLWELL, of the city and county and State of New York, have invented a certain new and improved Valve for Sugar-Pans; and I do hereby declare the following to be a full, clear, and exact description of the same, reference being had to the annexed drawing making part of this specification, in which—

Figure 1 shows a vertical section through the centre of said valve, and

Figure 2 is a view of said valve turned bottom side up.

The object of this invention is to facilitate and more perfectly control the escape of the sugar from the pan. This object I accomplish by making my valve-chest globular in form, and forming upon one side thereof a nozzle, fitted with a poppet-valve upon a stem running through the centre of said chest, and which stem is also fitted with a breaker upon its upper end, to break the crust which sometimes forms in the nozzle of the valve-chest or neck of the pan, and which, when the old style of valve or cock is used, prevents the flow of the sugar therefrom.

To enable those skilled in the arts to which my invention appertains to make and use the same, I will proceed to describe the construction and operation thereof.

Similar letters of reference represent corresponding parts of the different figures in the annexed drawing.

The valve-chest is shown in the drawing by *a*, the valve by *b*, the valve-stem by *d*, the breaker by *c*, the valve-stem guide by *e*, and the lever for working the valve by *f*.

Now, let this chest be bolted to the neck of the pan by the flange *v*, so as to make a joint impervious to the sugar or air, and let it be desired to draw out the sugar from the pan.

The operator takes hold of the lever *f*, and, by a single impulse of his hand, opens the valve wide, and at the same time breaks any incrustations that may have formed in the neck of the pan or nozzle to the valve, and leaves the sugar free to issue on all sides of the valve, throwing it against the curved wall of the chest, which is contracted at its lower end or mouth, so as to throw the sugar towards the centre from all sides, thus drawing it in a concentrated stream into the receiver.

In practice, the valve *b* is made of India rubber, and the valve-seat is ridged up, so as to clear itself of sugar, and insure a tight joint under the valve, and the lever *f* is made longer than shown in the drawing, and is secured by any known mechanical means to hold the valve tightly against its seat.

One end of the valve-stem guide *e* is fitted into a mortise made in the chest of the valve, and the other is held by a screw, in a flange cast on the chest, which screw may be readily taken out, and by which the valve-stem and breaker can be taken out of the chest, leaving the opening of the pan entirely unobstructed.

Having now described the object, nature, and practice of my invention, I claim, and desire to secure by Letters Patent—

1. In combination with a sugar-pan, a valve, enclosed in a globular chest, arranged so as to concentrate the sugar into a solid stream as it issues from the chest and pan into the receiver.
2. The use of a poppet-valve enclosed in a chest, in combination with a sugar-pan, substantially as described.
3. The use of the breaker *c* on the end of the valve-stem, to break the crust of the sugar, and clear the neck of the pan or nozzle of the valve-chest, and allow a free exit for the sugar, substantially as described.
4. Arranging the valve-stem guide *e* in the chest, substantially as described, by which it, the valve-stem and breaker, can be removed out of the chest, by simply taking out the screw in the end of said valve-stem guide.

LEWIS COLWELL.
